UNITED STATES PATENT OFFICE.

SAMUEL BLAKELY, OF GRAMPIAN, PENNSYLVANIA.

CURTAIN-POLE.

No. 819,507.

Specification of Letters Patent.

Patented May 1, 1906.

Application filed June 9, 1905. Serial No. 264,420.

To all whom it may concern:

Be it known that I, SAMUEL BLAKELY, a citizen of the United States of America, residing at Grampian, in the county of Clearfield and State of Pennsylvania, have invented certain new and useful Improvements in Curtain-Poles, of which the following is a specification, reference being had therein to the accompanying drawings.

10 My invention relates to certain new and useful improvements in curtain-poles, and contemplates the construction in which the constituent parts may be very easily and quickly assembled and which will be inexpensive and simple to manufacture.

More particularly, the invention embodies a curtain-pole comprising two sections terminating in inclined ends, which are rounded and which fit into a socket in the ornamental 20 head, said socket being of contour corresponding to the contour of said inclined ends, so that the union is effected between the ornamental head and the ends of the pole by the frictional contact of the aforementioned 25 elements.

The detailed construction will appear in the course of the following description, in which reference is had to the accompanying drawings, forming a part of this specification, like numerals designating like parts throughout the several views, in which—

Figure 1 is a perspective view in which the various parts are assembled, the curtain being shown as clamped between the sections of 35 the pole. Fig. 2 is a fragmentary vertical sectional view through the pole and the ornamental head, illustrating the peculiar contour of the end of the pole and of the socket in the head. Fig. 3 is a perspective view of 40 one section of the pole, illustrating a modification in which the end is split to form furcations. Fig. 4 is a fragmentary perspective view of a modification somewhat similar in construction to Fig. 3, but in which each section is formed with a plurality of radially-extending slots or openings, so as to increase 45 the number of furcations.

The curtain-pole A is preferably of cylindrical contour and embodies two sections or 50 halves 1, which are counterparts in construction. The sections 1 have their ends inclined and rounded, as at 2, so that when the said sections are assembled the adjacent ends will possess the contour of the frustum of a cone.

55 An ornamental head 4 fits over each end of

the pole, which of course is the meeting ends of the two sections, said head 4 being provided with a conical recess 5 of the same size as the ends of the curtain-pole within which 60 the said ends fit. A reinforcing metallic ring 6 is employed, which serves to brace the ornamental head under the pressure or resiliency of the ends of the curtain-pole. Between the sections 1 a longitudinal space 7 65 occurs, through which the curtain is inserted and in which it is held by friction.

In the modification shown in Fig. 3 the end of each section is split longitudinally, as at 3, for a short distance, so as to form on the end 70 of each section furcations, which owing to the resiliency of the wood employed will naturally tend to spread apart, thereby insuring a greater degree of pressure and frictional contact within the socket 5 of the head 4. 75

Of course the ends 2 may be split in any number of places, so as to form greater or less number of furcations, as the case may be, without departing from the spirit of the invention. 80

The curtain-pole is suspended by brackets or supports which are screwed or otherwise held in the framework and which are provided adjacent the ends with depressions of contour corresponding to the contour of the 85 pole and in which the said pole rests.

It is obvious that numerous changes may be made. For instance, I may employ extraneous means, such as a wedge or a serrated pin of conical contour to force the sections apart instead of relying solely on the resiliency of the wood, although these elements are not absolutely necessary to perform the functions above set forth. The essential feature of the invention is the curtain-pole formed with inclined split ends, and I wish it to be understood that slight changes such as would suggest themselves in practical use and manufacture may be made without departing from the spirit and scope 90 of my invention as defined in the appended claim. 95

Having fully described my invention, I claim—

A curtain-pole formed of two semicylindrical sections, having flat adjacent faces throughout their length, and having the outer face of both sections tapered at each end, each tapered face having a plurality of slits, extending from the outer extremity of 105 the section to a point adjacent the beginning of the taper, the said tapered faces forming 110

frusto - conical ends on the pole when the sections are matched together, in combination with securing-heads engaging said conical ends on the pole, each head consisting of a solid cylindrical body having a conical opening of less length than the conical ends on the pole whereby the slotted ends of the sections will be clamped together as the securing-head is tightened on the conical end of the pole, a shoulder on the inner end of each securing-

head, and a ring clamped on said shoulder to hold the securing-head against splitting, substantially as described.

In testimony whereof I affix my signature in the presence of two witnesses.

SAMUEL BLAKELY.
